UNITED STATES PATENT OFFICE.

EARL T. PHELAN, OF JACKSON, MICHIGAN.

CUSHION-RIM.

1,391,074.

Specification of Letters Patent. Patented Sept. 20, 1921.

Application filed April 8, 1920. Serial No. 372,184.

To all whom it may concern:

Be it known that I, EARL T. PHELAN, citizen of the United States, residing at Jackson, in the county of Jackson and State 5 of Michigan, have invented certain new and useful Improvements in Cushion-Rims, of which the following is a specification.

This invention relates to an improved cushion rim for vehicle wheels and has as 10 one of its principal objects to provide a device of this character which may be employed in connection with the wheels of motor vehicles for supplanting the ordinary pneumatic tire.

15. The invention has as a further object to provide a rim employing resilient cushioning blocks and wherein the principle of a toggle will be embraced in conjunction with said blocks whereby a maximum cushioning 20 effect may be had from the blocks.

A still further object of the invention is to provide a rim employing a plurality of toggle members between the cushioning blocks and wherein said members may be 25 adjusted for varying the normal rigidity of the rim.

And the invention has as a still further object to provide a rim which may be readily adapted to substantially any conventional type of motor vehicle wheel.

30. Other and incidental objects will appear hereinafter.

In the drawings:

Figure 1 is a fragmentary section showing 35 my improved rim in connection with a conventional motor vehicle wheel.

Fig. 2 is a vertical section taken at substantially right angles to Fig. 1,

Fig. 3 is an elevation of one of the toggle 40 members employed, parts being broken away and shown in section,

Fig. 4 is an edge elevation of said toggle member,

Fig. 5 is a side elevation of one of the 45 cushioning blocks, and

Fig. 6 is an end elevation of one of said blocks, the block being partly broken away and shown in section.

In carrying the invention into effect, I 50 employ a channeled inner rim band 10 and a channeled outer rim band 11. Surrounding the outer band is a resilient tread 12 which may be formed of suitable rubber and is provided preferably with a hard rubber base or 55 lining 13 contacting the band. Seated in

the channel of the inner band 10 is an annular series of spaced cushioning blocks 14 and seated in the channel of the outer band 11 is a similar series of cushioning blocks 15, the blocks of the series being staggered. 60 Extending between the flanges of the respective bands at opposite sides of each of the blocks are stop rods 15' securing the blocks against creeping. The cushioning blocks are of similar construction and in 65 Figs. 5 and 6, I have shown one of said blocks in detail. As there illustrated, each of said blocks is formed with a base from which rises a medial semi-cylindrical rib 16 extending longitudinally of the base from end to end thereof. Base flanges 17 are thus defined at opposite sides of the rib and, as will be observed, the side faces of the rib merge with the upper faces of said flanges 70 to provide concave bearing seats 18 at the junctions between said rib and flanges while the side faces of the rib provide convex bearing seats 19 above the first seats. Formed in opposite sides of the block at the base of the rib are inclined sockets 20 located substantially midway between the ends of the 75 block.

The bearing blocks are, as particularly shown in Fig. 2, arranged to extend transversely of the rim bands fitting snugly 80 therein and bearing between the series of blocks is a plurality of toggle members. In 85 Figs. 3 and 4 of the drawings I have shown one of said members in detail. As will be observed, each of the toggle members is 90 formed of inner and outer sections. The inner section comprises a cross head 21 having merging convex and concave bearing faces 22 and 23 respectively and rising from the base of the head at a point substantially midway between its ends, is a centering stud 24. Extending from the base of the head in a direction opposite to 95 said stud are spaced parallel posts 25 suitably secured to the head and disposed adjacent opposite ends thereof. Like the inner section, the outer section of each of said toggle members is formed with a cross head 26 having merging convex and concave bearing faces 27 and 28 respectively, 100 and rising from the base of the head at a point substantially midway between its ends is a centering lug 29 similar to the lug 24. Extending from the end portions of the head in a direction opposite to said lug 110

are spaced parallel sleeves 30 which freely receive the posts 25 of the inner section and threaded upon said posts to coact with the sleeves are adjusting nuts 31. Attention is now directed to the fact, as particularly shown in Fig. 4, that the sections of each of the toggle members are assembled so that the cross heads 21 and 26 are reversely directed. Consequently, the toggle members 5 may be assembled with the cushioning blocks 14 and 15 to bear therebetween in the manner shown in Fig. 1. As will be observed, the studs 24 of the cross heads 21 are fitted in the sockets 20 of the inner 10 series of blocks 14 while the studs 29 of the cross heads 26 are engaged in the sockets of the outer series of blocks, these studs being provided with beveled end faces to prevent gouging of the blocks. The cross 15 heads will thus be supported upon the blocks so that the convex faces 22 and 27 of said heads will engage in the seats 18 of the blocks while the concave faces 23 and 28 of the heads engage the seats 19 of the blocks. The toggle members will accordingly coact with the blocks for centering and sustaining the outer rim band with respect to the inner rim band and, as will be seen, when the outer band shifts with respect to the inner band, under the weight 20 of a load, the toggle members will tend to bear into the blocks for thus cushioning the load. In this connection, it will be observed, as best shown in Fig. 1, that when 25 the inner band moves downwardly in eccentric relation to the outer band, the toggle members at the upper and lower side portions of the rim will be rocked toward alined position so that the convex bearing faces of said members will press into the concave seats of the blocks, the toggle members thus tending to compress the blocks therebetween. On the other hand, the concave faces of the cross heads of the toggle 30 members will coact with the convex seats of the ribs 16 of the blocks for resisting rebound of the inner rim band. Thus, by the arrangement shown, a maximum cushioning effect will be obtained from the blocks. 35 Further, as will be observed, the cross heads of the toggle members will coact with the blocks for cushioning lateral shock or strain upon the rim. By simply adjusting the nuts 31 of the toggle members to vary the effective length thereof, the normal rigidity of the rim may, as will be at once appreciated, be in turn varied so that the rim may accordingly be easily adapted for use upon vehicles of different weights. Further, by 40 this adjustment of the toggle members, a maximum cushioning effect may be obtained from the rim for any particular vehicle. Loosely fitted upon the posts 25 of each of the toggle members is a locking strip 31' 45 extending transversely between said posts 50

and the ends of which are bent up to confront the nuts 31 for thus locking said nuts in adjusted position.

In the drawings, I have shown my improved rim in connection with a conventional type of motor vehicle wheel 32 provided with a felly band 33 and equipped with clamping bolts 35 carrying wedges 36. As will be seen, the rim of the present invention may, like an ordinary demountable 75 rim, be slipped over the felly band of the wheel to coact therewith when, after the wedges have been properly positioned in the manner shown in Fig. 2, the nuts of the clamping bolts may be adjusted for 80 tightly binding the rim in place. Accordingly, the rim of the present invention may be readily used in connection with the large percentage of motor vehicles at present equipped to receive demountable wheel rims. 85 However, I do not wish to be limited in this regard since, as will be seen, the rim band 10 may be applied directly to a wheel felly for displacing the usual felly band and permanently connecting the rim with the wheel. 90 I accordingly reserve the right to all such adaptations of the invention as may fall within the spirit of the appended claims.

Having thus described the invention, what is claimed as new is:

1. A cushion rim including inner and outer rim bands, cushioning means carried by the bands respectively, and toggle members bearing between said means to rock thereagainst sustaining the bands with respect to each other. 95
2. A cushion rim including inner and outer rim bands, cushioning means carried by the bands respectively, the means of one band being staggered with respect to the means of the other band, and toggle members bearing between said means to rock thereagainst sustaining the bands with respect to each other. 105
3. A cushion rim including inner and outer rim bands, cushioning blocks carried by the bands respectively, and toggle members bearing between said blocks to rock thereagainst sustaining the bands with respect to each other. 110
4. A cushion rim including inner and outer rim bands, cushioning means carried by the bands respectively, toggle members bearing between said means to coact therewith sustaining the bands with respect to each other, and means for adjustably varying the length of said members. 115
5. A cushion rim including inner and outer rim bands, cushioning blocks carried by the bands respectively, and toggle members extending between the blocks for sustaining the bands with respect to each other and having cross heads coacting with the blocks. 125
6. A cushion rim including inner and 130

- outer rim bands, cushioning blocks carried by the bands respectively and provided with sockets, and toggle members extending between the blocks and having cross heads 5 coacting therewith and formed with centering studs engaging in said sockets, the toggle members bearing between the blocks for sustaining the bands with respect to each other.
- 10 7. A cushion rim including inner and outer rim bands, cushioning blocks carried by the bands respectively and each provided with concave and convex seats, and toggle members extending between the blocks and 15 provided with cross heads having concave and convex bearing portions fitting the seats of said blocks, said toggle members coacting between the blocks for sustaining the bands with respect to each other.
- 20 8. A cushion rim including inner and outer rim bands, cushioning means carried by the bands respectively, toggle member sections coacting with the means upon one of the bands and provided with sleeves, toggle member sections coacting with the means upon the other of the bands and provided 25 with posts freely received in said sleeves, and nuts carried by said posts to coact with the sleeves for supporting the sections upon
- each other whereby the sections will coact 30 between the cushioning means for sustaining the rim bands with respect to each other, the nuts being adjustable upon the posts for spreading the sections.
9. A cushion rim including inner and 35 outer rim bands, cushioning blocks carried by the bands respectively, stop means upon the bands limiting the blocks against creeping, and toggle members bearing between said blocks to rock thereagainst sustaining 40 the bands with respect to each other.
10. A cushion rim including inner and 45 outer rim bands, cushioning means carried by the bands respectively, sectional toggle members bearing between said means to coact therewith sustaining the bands with respect to each other, means for adjustably spreading the sections of said members, and locking means for said last mentioned means.
11. A cushion rim including inner and 50 outer rim bands, cushioning means carried by the bands respectively, and toggle members swingingly connected by said means to rock thereagainst and bear between said means sustaining the bands with respect to 55 each other.

In testimony whereof I affix my signature.
EARL T. PHELAN. [L.S.]
